[57] CLAIM

The ornamental design for a fishing reel support, as shown and described.

DESCRIPTION

FIG. 1 is a side elevational view of my design for a fishing reel support showing the fishing reel in outline form supported in position;

FIG. 2 is a left end view of FIG. 1;

FIG. 3 is a rear view of FIG. 1; and

FIG. 4 is a top view of FIG. 3.

The fishing reel shown in dotted lines in FIG. 1 is for illustrative purposes only and forms no part of the claimed design.
